C. S. WINDSOR.
SELF LOCKING PIVOTED JOINT.
APPLICATION FILED FEB. 17, 1919.

1,349,032.

Patented Aug. 10, 1920.

Inventor:
Cecil Stanley Windsor,
By: B. Singer, Atty.

UNITED STATES PATENT OFFICE.

CECIL STANLEY WINDSOR, OF LONDON, ENGLAND.

SELF-LOCKING PIVOTED JOINT.

1,349,032.

Specification of Letters Patent. Patented Aug. 10, 1920.

Application filed February 17, 1919. Serial No. 277,569.

To all whom it may concern:

Be it known that I, CECIL STANLEY WINDSOR, trading as Jas. Bartle & Co., a subject of the King of England, residing at 236 5 Lancaster road, Notting Hill, London, England, (whose post-office address is 236 Lancaster road, Notting Hill, London, England,) have invented certain new and useful Improvements in and Relating to Self-Lock- 10 ing Pivoted Joints, of which the following is a specification.

This invention relates to pivoted joints of the kind which are automatically locked in any desired position.

15 According to my invention the joint is locked by a cam block engaging free rollers and can only be unlocked and moved around its pivot by means of a special unlocking device which engages between the rollers and is fixedly or removably mounted to rotate co-axially with the pivot of the joint.

20 My invention is intended more especially for application to motor and other vehicle hoods, and motor and other wind screens, 25 but it may be applied to any type of instrument, apparatus, or mechanism to which such a self-locking pivoted joint is applicable.

I will now describe my invention with 30 the aid of the accompanying drawings which are to be deemed illustrative only, as modifications and rearrangements of details may be effected without departing from the spirit of the invention.

35 Figure 1 is a partly sectional elevation of the device;

Fig. 2 is a side elevation of same;

Fig. 3 is a section taken on the line 3—3 in Fig. 1;

40 Fig. 4 is an elevation of one of the joint members;

Fig. 5 is an elevation of the unlocking device; and

Fig. 6 is a section taken on the line 6—6 45 in Fig. 5.

Throughout these drawings like characters of reference denote like parts.

For the sake of clearer demonstration the device may be divided into three principal 50 parts thus:—the two members *b* and *c* forming the pivoted joint and the unlocking device *a*.

The housing or casing of the joint-member *c* is bored so as to form a race for the 55 locking details, and is furnished axially with a pivot stem *d* around which the other mem-

ber *b* of the joint, the unlocking details and the locking device *a* are free to rotate. The member *c* is provided with a flanged base *c'* having bolt holes *c*² by means of which it 60 can be secured to the motor vehicle hood or other part.

Journaled upon and free to rotate around the pivot stem *d* is a block *e* having a cam or cams *e'* on its periphery (two are shown 65 in the drawings). In the annular space between the block *e* and the outer boundary of the boring in the member *c* a number of pairs of loose arcuate segments *g*, (one pair for each cam *e'* on the block *e*) are 70 placed so as to be freely movable around the annular space or race in the member *c*. Each segment *g* is provided with a housing to receive the free end of a spring *h* so as to couple every two together to form a pair, 75 and is recessed at its other end to receive an anti-friction roller *f*. These segments and rollers are so disposed around the block *e* that a roller is on each side of a cam on the block, so that if there is only one cam, 80 there would be only two segments and rollers, if two cams (as shown in the drawings) four segments and rollers, three cams, six segments and rollers, and so on.

The rollers *f* and the arcuate segments 85 are prevented from revolving in the annular space surrounding the block *e* by reason of the enlargements forming the cams *e'*, and the pressure of the springs *h* is such as to force the segments apart and consequently 90 to press the rollers toward the cams so that the block *e* cannot be rotated. This is the normal or locked position of the parts. The unlocking of the device is effected by the element *a* hereinafter described.

95 The member *b* of the joint is either formed integrally with the block *e* or, as shown in Figs. 1 and 4, it is centered by the aperture *i* upon the pivot stem *d* and is pierced by two holes *k* which fit over and engage studs *l* upon the cam block *e*, being retained in position by the cover plate *m* of the unlocking device *a*.

The unlocking device *a* is centered at *n* (Fig. 5) upon the pivot stem *d*, being superimposed upon the member *b*, and is there retained by the screw *o* and washer *p*. Its cover plate *m* is furnished with a lug or lugs *q*, arranged at right angles to its face as shown in Fig. 6, and so shaped and constructed as to bridge the space between each two contiguous rollers *f* and to press same 110

slightly back against the pressure of their springs *h*; also each lug will abut against a shoulder *b'* on the member *b* which latter, as previously stated, is mounted on the stem 5 *d* beneath the device *a*; see Figs. 2 and 3.

The joint illustrated is manipulated in the following manner:—When it is desired to alter the angular position of the member *b* relatively to the member *c*, the unlocking 10 device *a* is moved in the same rotary direction as that in which the element *b* is required to be moved, whereupon the device *a* is, by reason of the clearance *q'* between the lugs *q* and rollers *f*, thrown slightly out of 15 line with the member *b* but its lugs *q* force the forward rollers *f* away from the cam surface *e'* in a circular direction, and also by abutting against the shoulders *b'* the said lugs cause the member *b* and the cam 20 block *e* to rotate around the pivot stem *d*, as the rearward rollers *f* cannot act to prevent this. When released the parts will remain in the position where left and it will be obvious that the member *b* is incapable of 25 being moved relatively to the member *c* except through the co-operation and by the movement of the unlocking device *a*.

It will be observed that when rotating the unlocking device *a* the cam block *e*, segments 30 *g* and rollers *f* all rotate together and carry with them the member *b* secured to the block *e*. It will also be noticed that the parts of the joint are effectively locked against relative movement whether the unlocking device *a* is in the position shown in 35 the drawings, or whether it is entirely removed therefrom, such removal being advisable when it is desired to prevent the unauthorized relative movement of the members *b* and *c* of the joint.

Having fully described my invention, what I claim and desire to secure by Letters 40 Patent is:—

1. A self-locking pivoted joint comprising two parts pivoted together, a cam-block 45 secured to one of the parts, free rollers in a

race in the other part normally locking the cam-block against movement, shoulders on said part and a device mounted to rotate co-axially with the pivot of the joint, lugs on said device to engage between the rollers and to bear against said shoulders for the purpose of unlocking the parts and effecting their relative movement.

2. A self-locking pivoted joint comprising two parts pivoted together, a cam-block secured to one of the parts, free rollers in a race in the other part, shoulders on said part, spring controlled arcuate segments also free to move in the race and bearing 50 against the rollers so as to cause them normally to lock the cam-block against movement, and a device mounted to rotate co-axially with the pivot of the joint, lugs on said device to engage between the rollers and to bear against said shoulders for the purpose of unlocking the parts and effecting their relative movement.

3. A self-locking pivoted joint comprising two parts pivoted together, a cam-block 70 secured to one of the parts, free rollers in a race in the other part, shoulders on said part, spring controlled arcuate segments also free to move in the race and bearing against the rollers so as to cause them normally to lock the cam-block against movement, and a device carrying lugs adapted to engage between the rollers to hold them back against the spring pressure on the free 75 arcuate segments and to bear against the shoulders on said other part, said device being mounted to rotate co-axially with the pivot of the joint for the purpose of unlocking the parts and effecting their relative movement.

In testimony whereof I have hereunto set my hand in presence of two subscribing witnesses.

CECIL STANLEY WINDSOR.
